JABEZ ALEXANDER, OF NASHUA, NEW HAMPSHIRE.

Letters Patent No. 84,983, dated December 15, 1868.

IMPROVEMENT IN DEVICE FOR SINGEING HORSES.

The Schedule referred to in these Letters Patent and making part of the same.

To all whom it may concern:

Be it known that I, JABEZ ALEXANDER, of Nashua, county of Hillsborough, State of New Hampshire, have invented a new mode by which the hair is singed or burned off, instead of clipping with shears, horses or other animals.

My invention consists in constructing a metallic gas-burner, of a convenient size and shape, that gas may be burned in a broad, wide blaze, and, at the same time, be carried to any part of the animal by means of an elastic tube, which connects the burner to a common gas-pipe.

The following is a correct description thereof, reference being had to the accompanying drawings, and letters marked thereon, making a part of this specification.

Figure 1 is a perspective view.
Figure 2, a sectional view.

In fig. 1, letter B is a cock, which regulates the amount of gas burned.

In fig. 2, letter C is a vacuum, through which the gas passes.

Letter D is an elastic tube, which connects the burner to the gas-pipe from which the gas is taken.

I am aware there is a great variety of metallic gas-burners, which are of a different construction, and for a different object than that of mine, all of which I disclaim.

What I claim as my invention, and desire to secure by Letters Patent, is—

The metallic gas-burner, when substantially arranged as and for the purpose described.

JABEZ ALEXANDER.
